UNITED STATES PATENT OFFICE.

ROSWELL A. MOORE, OF BERLIN, CONNECTICUT, ASSIGNOR TO WATERBURY BUCKLE COMPANY, OF WATERBURY, CONNECTICUT, A CORPORATION.

GARMENT-SUPPORTER CLASP.

No. 922,799.

Specification of Letters Patent.

Patented May 25, 1909.

Application filed July 6, 1908. Serial No. 442,036.

To all whom it may concern:

Be it known that I, ROSWELL A. MOORE, a citizen of the United States, residing at Berlin, in the county of Hartford and State 5 of Connecticut, have invented a new and useful Improvement in Garment-Supporter Clasps; and I do hereby declare the following, when taken in connection with the accompanying drawings and the numerals of reference marked thereon, to be a full, clear, and exact description of the same, and which said drawings constitute part of this specification, and represent, in—

Figure 1 a view in front elevation of a 15 garment-supporter clasp constructed in accordance with my invention. Fig. 2 a view thereof in vertical section. Fig. 3 a detached view in inside elevation of the outer jaw. Fig. 4 a corresponding edge view 20 thereof.

My invention relates to an improvement in garment-supporter clasps, the object being to produce a simple, compact and convenient clasp of superior gripping power.

In carrying out my invention I turn the 25 lower end of the outer jaw 2 inward and upward and back on itself so as to form an integral but yielding lip 3 which, in the construction shown, embeds itself in the corrugations of a rubber pad 4 mounted upon the 30 outer face of the lower end of the inner jaw 5. The said inner and outer jaws may be of any approved construction. As herein shown

they are operated by a finger-lever 6 having trunnions 7 passing through perforations in 35 ears 8 turned forward at a right angle from the side edges of the inner jaw 5. The said lever 6 when swung upward into its closed position draws the two jaws together and locks them in their closed and garment- 40 gripping positions against the tension created by embedding the yielding lip 3 in the rubber pad 4. The inner jaw, as shown, is provided at its upper end with a wire loop 9 by means of which the clasp is suspended from webbing 45 or tape as the case may be.

I claim:—

In a garment-supporter clasp, the combination with two jaws one of which is provided at its lower end and upon its inner face 50 with a yielding lip, of a rubber pad located upon the lower end of the inner face of the other jaw for co-action with the said lip which embeds itself in the pad, and a finger-lever pivotally connected with the inner jaw 55 and co-acting with the outer jaw for forcing the two jaws together and locking them in their closed positions with the said yielding lip in the rubber pad.

In testimony whereof, I have signed this 60 specification in the presence of two subscribing witnesses.

ROSWELL A. MOORE.
